DEVICE FOR PROJECTING MOVING MESSAGE

Ferdinand C. Forney, % Roto-See Co., 3067 Kleeman Road, Cincinnati 11, Ohio

Filed May 13, 1959, Ser. No. 812,927

2 Claims. (Cl. 38—27)

This invention relates to advertising devices and more particularly to an advertising device for projecting a continuously moving message on a screen.

An object of this invention is to provide a device which projects a continuous message from a film drum onto a screen on which the message may be viewed.

A further object of this invention is to provide a machine of this type in which the message comprises a plurality of sloping or helical lines on the film drum and in which the drum is moved axially and rotated while light is projected through a section thereof, to project the message on the screen.

A further object of this invention is to provide a device of this type in which the drum moves axially in one direction, while rotating at a speed which permits projection of the message and in which the drum is moved rapidly at the end of the message in the opposite direction to the start of the message, so that the message is repeated.

The above and other objects and features of the invention will be apparent to those skilled in the art to which the invention pertains, from the following detailed description and the drawings, in which:

FIG. 1 is a view in front elevation of an advertising device constructed in accordance with an embodiment of this invention, fragmentary portions of a bus wall and of a hand rail being shown in section in association therewith;

FIG. 2 is a plan view of the device illustrated in FIG. 1 with the upper case half removed, a portion of a screen thereof being broken away and in section to reveal details of structure;

FIG. 3 is a view in section taken on the line 3—3 in FIG. 2, case supporting brackets being partly broken away;

FIG. 4 is a view in section taken on the line 4—4 in FIG. 3;

FIG. 5 is a view in section taken on the line 5—5 in FIG. 3, part of a film strip being broken away to reveal details of structure;

FIG. 6 is an enlarged, fragmentary view in transverse section of a movable film drum and a film strip which form a part of the device, a film clamp being shown in closed position in full lines and in released position in dot-dash lines;

FIG. 7 is a fragmentary view in section taken on the line 7—7 in FIG. 2;

FIG. 8 is a fragmentary view in side elevation of the film strip removed from the film drum;

FIG. 9 is a view in section taken on the line 9—9 in FIG. 3;

FIG. 10 is a perspective view of the upper portion of a main shaft with the movable drum removed;

FIG. 11 is a view in section taken on the line 11—11 in FIG. 5;

FIG. 12 is a view in section taken on the line 12—12 in FIG. 5;

FIG. 13 is a view in section taken on the line 13—13 in FIG. 5; and

FIG. 14 is a view in section taken on the line 14—14 in FIG. 3.

In the following detailed description, and the drawings, like reference characters indicate like parts.

In FIG. 1 is shown an advertising device constructed in accordance with an embodiment of this invention which

2

includes upper and lower case halves 13 and 14. The upper case half 13 carries resilient mounting brackets 16 and 17. A clamp arm 18 is mounted on the bracket 16 and can be attached to top or ceiling panel 19 of a bus, or the like, by bolts 21. A clamp 22 is mounted on the bracket 17 and can engage the horizontal hand rail 23 of the bus. The device can thus be mounted inside a bus, or the like, in a position to be viewed by passengers therein.

10 The casing halves 13 and 14 are held together in assembled relation by bolts 24, 25, and 26 (FIG. 2). Details of construction of the bolt 26 are shown in FIG. 9. The upper end of bolt 26 is releasably threaded in a boss 28 which is integral with the upper case half 13. The lower end of the bolt 26 is rotatably mounted in a bore 29 of a boss 31, which is integral with the lower case half. An enlarged portion 27 of the bolt 26 turns in a counter-bore 33. A head 34 of the bolt 26, which may be square in transverse cross-section, can receive a key (not shown) for turning the bolt. A compression spring 36, mounted on the shank of the bolt, prevents inadvertent turning of the bolt. The spring engages the boss 31 and a washer 38 mounted on the shank of the bolt. The washer 38 in turn engages a pin 41 which extends through the bolt 26.

20 A main frame plate 43 (FIGS. 2 and 3) is mounted inside the lower case half 14 parallel to and spaced above the bottom thereof. The main frame plate 43 is mounted on lugs 44 (FIG. 3) which are integral with the lower case half. Screws 46 attach the main frame plate 43 to the lugs 44.

25 A stationary, hollow drum 47 is mounted on the frame plate 43. As shown in FIGS. 3 and 5, the drum is provided with a slot 48 through which light is projected from a lamp 49. Otherwise, the stationary drum is opaque. The upper end of the drum 47 is partially closed by a top or cap 51 (FIGS. 2 and 5), which fits over the upper edge of the stationary drum 47 and is removably held in place thereon by spring clamps 52, one of which is shown 30 in detail in FIG. 5. The cap 51 includes a cross bar 53 which spans the cap. The lamp 49 is mounted on the underside of the cross bar 53. In addition, a first lens holder 54 (FIG. 3) is attached to the underside of the cross bar 53. A second lens holder 56 is attached 35 to the outside of the stationary drum overlying the slot 48.

40 A movable drum 58 is mounted inside the stationary drum. The movable drum 58 is rotatably mounted on an upright shaft 59 and can move axially along the shaft 59. The upper end of the shaft 59 is received inside a bearing member 57 in the cross bar 53. The movable drum carries a web or strip of film 60 on which a message is printed. Light is projected by the lamp 49 through a section of the film and through appropriate lenses in the lens holders and through the slot 48 onto a mirror 61 (FIGS. 2 and 3) which reflects the light onto a ground glass screen 62 (FIGS. 1 and 2) or the like, where the message appears in moving lettering as the movable drum turns and moves axially. As shown, the screen is of long oblong shape and an elongated moving image appears 45 thereon.

50 As shown in FIG. 8, the film strip 60 carries a message which includes a plurality of rows or lines 63 of lettering forming a message, which lines slope as shown in FIG. 8. As the movable drum is turned and is advanced axially 55 the message is transmitted through the slot 48 (FIG. 2) onto the ground glass screen 62 (FIGS. 1 and 2).

55 The film strip has a plurality of perforations 64 along the lower edge thereof, as shown in FIG. 8. The movable drum includes a ring portion 66 having an outwardly extending flange 67 (FIGS. 5 and 14) on which the lower edge of the film strip 60 rests. A plurality of pins 68, one 60 of which is shown in FIG. 14, extend outwardly of the

ring portion 66 and engage the perforations 64 to hold the film strip in place. End portions 70 and 71 (FIG. 8) of the film strip contain rows of perforations 72. When the film strip is mounted on the movable drum, the end portions overlap, as shown in FIG. 6, and are engaged by a clamp 73 which forms a part of the movable drum. The clamp 73 includes a stationary, upright arm 74 and a clamp arm 76 hinged to the upright arm 74 on a pivot 77. Pins 78 mounted in the upright arm 74 engage the perforations in the ends of the film strip and are received inside openings 79 in the clamp arm.

The movable drum rides on a bearing member 81 (FIGS. 3 and 5) which spans the stationary drum. The upright shaft 59 rotates inside a bearing 82 (FIG. 5) mounted in the bearing member 81. The bearing 82 supports the movable drum. Ends of the bearing member 81 carry rollers 83 and 84 (FIGS. 2, 5 and 7). The rollers 83 and 84 ride in slots 85 in the walls of the stationary drum, one of which is shown in FIG. 7. The rollers 83 and 84 ride on cams 86 and 87, respectively (FIG. 2). The cams are mounted on a cam shaft 88 (FIGS. 5 and 7). As the cam shaft 88 turns in a clockwise direction, as shown by arrows in FIG. 7, the cams slowly raise the drum until a radial portion 89 of the cams is reached, whereupon, the bearing member and the movable drum can fall rapidly to an initial position at which the cams start to raise the movable drum again. In FIG. 5, an intermediate position of the drum is shown in full lines. The uppermost position reached by the drum before it falls is shown in dot-dash lines.

While the cams raise and lower the movable drum, the movable drum turns with the upright shaft 59 (FIG. 5). A slotted sleeve 91 is mounted on the shaft 59. The sleeve 91 has two upright slots 92 and 93. As shown most clearly in FIG. 10, ends of a pin 94 are received in the slots of the sleeve 91. The pin 94 extends through the shaft 59 (see FIGS. 5 and 11) and is received in the slots so that the sleeve 91 turns with the shaft 59, but the sleeve can move lengthwise of the shaft as the movable drum 58 is raised and lowered. The movable drum 58 has a hub 96 which surrounds the sleeve 91. A lug 97 is mounted on the interior of the hub 96, as shown in FIG. 12. The lug 97 can slide along a groove 98 in the sleeve so that the movable drum rotates with the shaft 59. A washer 99 is mounted on the shaft 59 overlying the sleeve 91. The washer 99 includes a flat side 100 which can be aligned with the groove 98, as shown in FIG. 10. When the washer 99 is in the position shown in FIG. 10, the upper end of the groove 98 is open so that the movable drum can be moved into position. The washer 99 is held down by a compression spring 101 which bears against a washer 102 mounted on the shaft 59.

The movable drum and the cam shaft are both driven by a motor 103 (FIG. 2) having a shaft 104. As shown in FIG. 4, the shaft 104 carries a worm 105 which drives a worm wheel 106. The worm wheel 106 drives a shaft 107 carrying a worm 108. The worm 108 drives a worm wheel 109 at the lower end of the shaft 59. As shown in FIG. 5, shaft 59 carries a worm 112 which drives a worm wheel 113 mounted on the cam shaft 88.

As the movable drum 58 rotates, it moves gradually upwardly along the shaft 59 while the message on the film strip is projected on the ground glass screen 62 (FIG. 1). When the end of the message is reached, the rollers 83 and 84 (FIG. 2) are reached by the radial sections of the cams (see FIG. 7), and the drum drops back to a starting or initial position of the film strip, whereupon the message is projected over again.

The device illustrated in the drawings and described above is subject to structural modification, without departing from the spirit or scope of the appended claims.

Having described my invention, what I claim as new and desire to secure by Letters Patent is:

1. A device for projecting a moving message on a screen which comprises a drum, a rotatable shaft, means for mounting said drum for rotation with and for axial movement along said shaft, means for mounting a film strip on said drum coaxially therewith, there being a plurality of lines of message on said film strip, means for rotating said shaft to rotate the drum, a bearing member supporting said drum, a cam follower mounted on said bearing member, a cam shaft connected to said rotatable shaft to be driven in timed relation therewith, a cam on said cam shaft engaging the cam follower for axially advancing said drum in timed relation to rotation of the drum, means inside the drum for projecting light through a selected portion of the film strip, and a screen on which the light is projected as a moving message.

2. A device for projecting a moving message on a screen which comprises a drum, an upright shaft, means for mounting said drum for rotation with and for axial movement along said shaft, means for mounting a film strip on said drum coaxially therewith, there being a plurality of lines of message on said film strip, means for rotating said shaft to rotate said drum, a bearing member supporting said drum, a cam follower mounted on said bearing member, a cam shaft connected to said upright shaft to be driven in timed relation therewith, a cam on said cam shaft underlying the cam follower, the cam being adapted to engage and raise the cam follower and the drum in timed relation to the drum rotating means, the cam lowering the cam follower when the drum reaches a predetermined height, whereby the drum falls to a predetermined initial height, means inside the drum for projecting light through a selected portion of the film strip, and a screen on which the light is projected as a moving message.
